UNITED STATES PATENT OFFICE.

ANNA NOTT SHOCK, OF NEW YORK, N. Y.

HAND-LOOM.

1,274,948.

Specification of Letters Patent. Patented Aug. 6, 1918.

Application filed January 26, 1918. Serial No. 213,881.

To all whom it may concern:

Be it known that I, ANNA NOTT SHOCK, a citizen of the United States, and a resident of the city of New York, borough of Manhattan, in the county and State of New York, have invented a new and Improved Hand-Loom, of which the following is a full, clear, and exact description.

This invention relates to weaving and has particular reference to hand looms.

Among the objects of the invention is to provide a hand loom particularly designed or constructed for rapid and satisfactory use when positioned upon a table, desk or the like.

More definitely stated I provide by this new mechanism a loom so constructed that the beater even though it constitutes a part of a machine which as a whole occupies a minimum amount of vertical space above the table or other support, yet may be operated for beating purposes through a wide space with respect to the longitudinal movement of the fabric that is being woven. In other words while the beater in machines commonly in use supported upon the floor has a pivotal or swinging movement from the axis adjacent to the floor in order to provide the proper amount of throw or movement of the beater it is obvious that the same amount of throw cannot be accomplished in a loom of the type herein indicated when pivotal movement alone is depended upon.

Another object of the invention is to provide improved facilities for manipulating the heddle frame providing for an easy means for lifting the heddle frame and holding it in lifted position while both of the operator's hands are free for the purpose of adjusting the weft threads or other purposes.

A still further object of the invention is to provide a means for locking the heddle frame in any desired position with sufficient firmness to hold the two sets of warp threads in any desired relation to each other.

Another object of the invention is to provide a relatively small and cheap loom construction, one that will occupy a minimum amount of space either in use or stored away, and which yet has a large capacity for actual service and one which enables the operator to weave a relatively long portion of cloth without readjustment of the warp and cloth.

Yet another object of the invention is to

provide a specific type of beater and supporting means therefor, having particular reference to the low type of machine already referred to.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is an elevation of the right side of the complete machine.

Fig. 2 is a plan view of the same.

Fig. 3 is a vertical longitudinal section on the line 3—3 of Fig. 2.

Fig. 4 is a vertical transverse section on the line 4—4 of Fig. 2.

Fig. 5 is a fragmentary detail view corresponding to a portion of Fig. 3, but indicating the beater in its forward position, and illustrating in comparison with Fig. 3 the combined sliding and pivotal movement of the beater; and

Fig. 6 is a small diagram indicating my loom supported upon a table and having a treadle to manipulate the heddle frame connections.

Referring now more particularly to the drawings, I show a loom comprising right and left panels 10 and 11 indicated as occupying parallel vertical planes and connected by transverse horizontal front and rear frame bars 12 and 13 respectively having any suitable supporting feet 14 serving to support the machine upon a table or other analogous elevated support as distinguished from the floor.

While I am not particularly concerned at this time with the design of the frame members I do indicate, however, that these members have height enough for the purpose of supporting the parts of the mechanism soon to be described. They are each shown with front and rear cutouts 15 and 16 for the purpose of facilitating access of the operator's hands to the work being performed.

In the otherwise open front end of the frame are secured the cloth beam 17 close above the bar 12, and the breast beam 18 above the cloth beam. At the rear end of the frame and supported between the rear

ends of the side panels 10 and 11 is the warp beam 19 just above the rear bar 13 and the free beam 20 above it.

The two sets of warp threads 21 and 22 are or may be connected to the cloth and warp beams in any suitable or approved manner and coöperate with the vertically reciprocating heddle frame 23 in any suitable or conventional manner for the purpose of changing the shed 24. I indicate the heddle frame as guided for reciprocations in a vertical plane by means of a pair of guides 25 secured upon the inner face of each side panel.

26 indicates a rock shaft journaled in and between the two side panels at the rear of the heddle frame and below the warp. At any convenient place, preferably at the center of its length the rock shaft is provided with a lever 27 which projects forward normally because of the action of springs 27' anchored at one end to the upper rear portion of the shaft and at the other end to the rear cross bar 13 and tending to rotate the rock shaft in a clock-wise direction as viewed in Fig. 3. Near its ends the rock shaft is provided with a pair of arms 28 which are arranged approximately at an angle of 90 degrees from the plane of the lever 27 and hence which project normally upward from the rock shaft. The outer ends of the arms 28 are bent at an angle or parallel to the axis of the rock shaft and have sliding engagement in the slots of a pair of bars 29 pivoted at 29^a at their front ends to the ends of the heddle frame, while the rear portions of the slotted bars have pivotal and sliding movement over fixed studs or pivots 29^b secured to the inner surfaces of the rear ends of the side plates 10 and 11. It will thus be seen that the force of the springs 27' will act or tend to act to rotate the rock shaft and its arms 28 to lift the heddle frame into the dotted line position of Fig. 3 forming an upper shed.

45 Any suitable means may be provided to manipulate the rock shaft in a counter clock-wise direction against the force of the springs 27' to lower the heddle frame and make a lower shed as shown in full lines in Fig. 3. To this end I provide a flexible connection 30 leading from the free end of the lever 27 rearward over a guide pulley 31 and thence forward over another pulley 32. This cord may be manipulated either by hand as applied to a handle 33, Figs. 2 and 3, or by means of a treadle 33', Fig. 6, when it is convenient for the operator to use her foot. It is to be noted in this connection that the means for manipulating the heddle frame may be practiced by an operator who has lost either a foot or a hand. When the treadle is used the heddle frame may be held down by the pressure of the foot on the treadle, but when the hand is used for

drawing the heddle frame downward the heddle frame may be held or preferably the connection 30 may be snubbed temporarily over a fastener 34 of any convenient construction. Furthermore by the means just described, or their equivalent, the heddle frame may be held at any position intermediate of its uppermost and lowermost positions, an expedient frequently useful in the application of ornamental features to the work or for other purposes.

The reader's attention is now called to the beater 37 comprising two main parts, the upright frame carrying a reed 38 and a base comprising a horizontal bar 39, and a pair of shoes 40 at opposite ends of the bar movable along guideways 41 at the bottom edges of the side panels 10 and 11. With respect then to these guideways 41 the beater as a whole is movable bodily in a horizontal direction toward and from the operator. The reed frame, however, is hinged at 42 to the base, the hinges being indicated as secured to the lower end of the reed frame posts 43 and the ends of the base bar 39, hence the reed portion of the beater with respect to the axis of the hinges 42 is adapted to swing forward especially during the latter part of the movement of the beater in a manner somewhat similar to the usual beater action. A pair of springs 44 are connected to the reed frame and the rear ends of the shoes 40, these springs having the function to tend to hold the reed frame upright, the rearward tilt of the reed frame under the force of the springs being limited to the vertical by reason of the frame striking against the upper part of the bar 39. Though the space between the breast beam 18 and the heddle frame 23 may be relatively deep or long, I am able to secure practically every advantage of the pivoted beater of the floor machine as well as maximum length of the work without readjustment even though the machine occupies a relatively slight vertical space. To this end the action is approximately as follows: With the beater frame left free it is held upward by the springs 44 and the operator pushing rearward thereon moves the entire beater along the guideways 41 with practically the same facility and freedom as the ordinary beater is moved rearward around the axis near the floor. This position then of the beater would be somewhat to the rear of that indicated in Fig. 3 giving a maximum shed. After adjustment of the weft the operator grasps the top of the beater and draws it bodily forward, the base gliding easily along the guideways 41 as far as desired. The operator then completes the movement of the beater by drawing downward upon the top thereof as shown in Fig. 5 against the force of the springs 44 which produces a true beating action. While in practice I recommend

a relatively slow or gentle movement of the beater as distinguished from a powerful blow or impact, still I have found that the pivotal movement of the beater will produce 5 a more uniform result than if a slideable movement only were depended upon. The shoes of the base are of such a length and the other parts of the beater are so related thereto that the beater may be moved to and 10 fro without cramping or material resistance without tilting or bending at the hinges, but when the final pivotal movement is desired the shoes have sufficient length in the guideways to hold the base from further sliding 15 movement when the top of the beater frame is given a slight downward thrust or impulse.

I claim:

1. The herein described hand loom designed for operation upon a table, the same comprising a frame having pairs of vertical and horizontal guides formed therein, a vertically movable heddle frame guided in one pair of the frame guides, and a beater comprising a base slideable in the other pair of guides and a reed portion pivoted to the base.

2. In a hand loom of the character set forth, the combination with a frame, a heddle frame movable up and down in the frame and means to control the warp, of a beater comprising a base slideable to and fro along the frame and a reed member hinged at its lower edge to the upper part 35 of the base and tiltable forward with respect to the base, the rearward tilt of the reed member being limited to the vertical by contact with the upper part of the base.

3. In a hand loom, the combination with 40 a frame having straight guideways formed along the lower edges of the sides thereof, of a beater comprising three features, viz. a base guided for bodily movement forward and rearward along said guideways, a reed 45 member pivoted to the frame and carried thereby during the bodily movements of the base and tiltable toward the operator independently of the base, and means acting upon the reed member tending to hold it in 50 a vertical plane.

4. In a hand loom, the combination with a frame and warp controlling means carried thereby, said frame being provided with a pair of straight horizontal guides adjacent 55 to its bottom, of a beater comprising a pair of horizontal shoes slideable along said guides, a rigid horizontal bar connecting said shoes, a reed frame, a pair of hinges securing the reed frame in position with the 60 lower edge thereof on top of said bar, the axis of the hinges being in front of the bar providing for the forward tilting of the reed frame with respect to the bar and shoes, the reed frame abutting against the top of 65 the bar limiting the rearward tilting of the

frame to the vertical, and resilient means acting upon the reed frame tending to hold it normally vertical over said bar.

5. The combination with a frame and warp controlling means carried thereby, of 70 a beater movable bodily along the frame, said beater comprising a base including a pair of horizontal shoes movable in the same horizontal plane toward the operator and a rigid bar connecting the shoes, said beater 75 also including a reed frame and hinges whereby the frame is connected to the bar and tiltable around the axis of the hinges toward the operator, and spring means acting between the reed frame and the shoes 80 tending to hold the reed in upright position.

6. In a hand loom, the combination of a rectangular frame including vertical side panels having vertical guides therein, a heddle frame guided for vertical movements between the side panels in said guides, and means to manipulate the heddle frame, said last mentioned means including a cord and means coöperating with the cord to positively hold the heddle frame at any desired elevation.

7. In a hand loom, the combination with a frame and a heddle frame movable up and down in the frame, of means to control 95 the position of the heddle frame comprising a rock shaft journaled in the frame back of the heddle frame and parallel thereto, a pair of slotted bars connected to the heddle frame, a plurality of arms fixed to the 100 rock shaft and having loose slideable engagement with the slotted bars, a lever connected to the rock shaft, and flexible means coöperating with the lever to hold it stationary temporarily with the heddle frame 105 at any desired elevation.

8. The herein described hand loom designed to be operated upon a table, the same comprising a frame having side panels, a beater movable along the front half of the 110 frame, a heddle frame back of the beater, guiding means for the heddle frame and means to move the heddle frame up and down along said guiding means, said heddle frame moving means comprising a rock 115 shaft journaled in the side panels of the frame back of the heddle frame, a spring acting upon the rock shaft tending to rotate it in one direction, a lever extending from the rock shaft, a cord attached to the 120 lever and extending thence along the frame to the front end thereof whereby the rock shaft may be rotated in the opposite direction, and connections between the rock shaft and the heddle frame whereby the heddle frame 125 will be moved up or down according to the direction of rotation of the rock shaft.

9. The combination with an elevated support, of a hand loom supported thereon,

said loom comprising a beater located entirely above the support and movable along the front half of the loom, a heddle frame back of the beater, and means to control the movement and position of the heddle frame, 5 said heddle frame controlling means including pivoted devices back of the heddle frame, a cord connected to the pivoted devices, and guiding means for the cord 10 whereby the cord may be manipulated below the loom and in front of said support.

10. The combination with an elevated support, of a hand loom supported thereon and comprising a frame, a beater located entirely above the support and movable along the front half of the frame, a heddle frame 15 guided in the frame for reciprocations in a

vertical plane, and controlling means for the heddle frame comprising a lever connected to the frame back of the heddle frame, connections between the lever and the heddle frame, means acting upon the connections tending to move the heddle frame in one direction, a cord connected to the lever and adapted when drawn to move the heddle frame in the opposite direction, 20 guide means directing the cord along the bottom of the loom over and downward in front of the support, and a treadle connected to the end of the cord whereby the operator may draw upon the cord or hold it with the heddle frame in any desired position 25 with her foot. 30

ANNA NOTT SHOOK.
